UNITED STATES PATENT OFFICE.

WILLIAM G. BETZ, OF CHICAGO, ILLINOIS.

COMBINATION MUSIC-CABINET AND PIANO-CASE.

1,145,828.

Specification of Letters Patent.

Patented July 6, 1915.

Application filed August 29, 1913. Serial No. 787,264.

To all whom it may concern:

Be it known that I, WILLIAM G. BETZ, a citizen of the United States of America, residing in Chicago, county of Cook, and 5 State of Illinois, have invented certain new and useful Improvements in Combination Music-Cabinets and Piano-Cases, of which the following is a specification.

My invention has to do with combination 10 piano cases and music cabinets, being directed more particularly to the provision of a piano case having a so-called music cabinet built therein or therewith and easily accessible by the player from in front of, or 15 when seated at, the piano. In connection with piano players and also with the ordinary piano, cabinets or shelves must usually be provided for storing the player rolls or sheet music but in using such arrangements 20 the player is usually forced to leave the piano in order to reach the rolls or music. To obviate this inconvenience I have provided a so-called music cabinet adapted to receive player rolls or sheet music and have 25 preferably positioned this cabinet in a place readily accessible by the player while seated at the piano, the cabinet being preferably placed directly beneath the top of the piano and provided with a door opening from the 30 front whereby access thereto may be had.

For a better understanding of my invention reference is to be had to the accompanying drawings in which like reference characters indicate like parts and in which— 35 Figure 1 is a face view of one form of piano case embodying my invention; Fig. 2 is an end view of Fig. 1 showing the piano closed; Fig. 3 shows the top part of the piano with the music desk or front panel 40 open and with the door of the music cabinet open; Fig. 4 shows a preferred manner of raising the top of the piano case and the music cabinet so as to provide access to the case interior; Fig. 5 is a longitudinal section along the line 5, 5, of Fig. 2, showing the elongated music cabinet located directly beneath the top board of the case; and Fig. 45 6 is a transverse section through the top portion of Fig. 2 showing the preferred construction of the case and cabinet.

Referring now more in detail to the preferred embodiment of my invention, a standard form of piano case A is shown having the usual top B, and positioned directly beneath the top board B is the preferred location of the so-called music cabi-

net C. A music desk or front panel D is also shown although it is to be understood that my invention is not limited to the use of a pivoted member D as is shown in the 60 preferred embodiment. The piano case A is one of a standard construction except for the improvement as will be hereinafter more particularly pointed out, and the front panel D is mounted in a customary manner 65 between pilasters 1 secured to the end walls 2, said member D being supported by hinged members 3.

In order to provide a readily accessible position for the cabinet C, I preferably arrange a chamber E between the top of the back frame F and the top B of the case. Any suitable cabinet or box-like structure for holding the music rolls or sheet music may be provided and I have shown an elongated box member having a back 4, a bottom 5 and end walls 6, which members 4, 5 and 6 are suitably secured preferably to the top B, by hinge members 11 and hooks 12, although it is to be understood that I 75 80 contemplate supporting the cabinet box in various ways, or according to the type of piano case employed.

At the front part of the cabinet C and the case A, a door 7 for the cabinet C is provided, this door being preferably hinged to the top B by means of hinges 8. The door 7 preferably extends across the front of the piano and rests against the face of the end walls 2 so as to furnish a good appearance 85 at the face of the piano although it is to be understood that this construction may be varied according to the design of the piano case employed. As will be seen in Fig. 6, the door 7 is preferably arranged to swing 90 outwardly, being pivoted along its upper edge, the dotted lines in Fig. 6 indicating the open position of the said door 7. I also preferably provide bracket members G for the purpose of holding the door 7 open so 95 that the player may have access to the cabinet C without having to open the door 7 each time it is desired to remove or replace the music matter. The bracket G which I 100 preferably employ is of a standard construction and so arranged that it normally tends to pull the door 7 inwardly under spring tension so as to hold it in its closed position and as the operator pulls the door 7 outwardly to open the cabinet, the initial 105 movement of the door is against the tension of the spring bracket G. But after the door

has been opened part way the tendency of the bracket G is to force the door open until it assumes a position as shown in Figs. 3 and 6. Likewise when the player desires to close the door, the initial closing movement is against the tension of the spring bracket G until a point near the closing position thereof is reached at which time the member G again acts to yieldingly hold the door closed. This form of bracket is standard and so well known I do not believe it necessary to illustrate it in detail, and although I contemplate using a bracket of this character, it is to be understood that this is not essential and may be dispensed with if desired.

In order to provide a means for grasping the door 7 whereby it may be opened, I preferably arrange a groove portion 7¹ against which the music desk D rests when in its closed position, and in order to open the door 7 the panel D is first opened when the fingers of the player may be inserted into the groove 7¹ to move the door 7 outwardly. In this way it is unnecessary for the operator to touch the face of the door 7 in opening it. It is to be understood of course, that this is the preferred construction, although as already pointed out, certain of these details may be varied depending upon the style and construction of the piano case employed.

In order to provide access to the interior of the piano case as is necessary at times, I preferably hinge the cabinet C and attached board B at 9 so that they may be simultaneously lifted upwardly and held by means of bracket members 10, as is shown in Fig. 4. Thus when it is desired to work at the interior of the piano case it is only necessary to push the top board B upwardly without removing any of the matter which may be in the cabinet and the cabinet and top board are held in an open position by the brackets 10. If it is desired to open the cabinet for cleaning or otherwise, it is only necessary to unlatch end hooks 12 and lift the top B.

It will be apparent from the foregoing that the combined piano case and so-called music cabinet are so constructed that a

player sitting before the piano has ready access to the cabinet for the purpose of removing or replacing music rolls or sheet music without necessitating leaving the piano seat, at the same time providing a comparatively cheap storage receptacle, and one which does not require any additional floor space.

Although in illustrating my invention I have chosen a certain form of construction, I contemplate applying it in other ways than that shown as it will be apparent that my invention may be readily applied to different designs of piano cases and therefore I do not desire to be limited to the exact structure as shown and described but aim to cover all that which comes within the spirit and scope of the appended claims.

What I claim as new and desire to secure by United States Letters Patent is:

1. A combination piano case and music cabinet comprising an upright piano case having a front panel pivotally supported at its sides, a music cabinet positioned immediately beneath the top of the case, a pivotally hung front door for the music cabinet having its lower end overlapping the front panel whereby when the front panel is drawn out at its bottom on its pivot an opening between the overlapping portions of the door and panel is caused whereby the door may be grasped to be opened.

2. A combination piano case and music cabinet comprising an upright case, a rigid top having an overhanging front edge, a music cabinet positioned immediately below the top and pivotally connected thereto at the rear thereof, a front door for the cabinet pivotally hung from the under side of the front edge of the top and having its lower edge overlapping the front panel of the case.

Signed by me at Chicago, county of Cook and State of Illinois, in the presence of two case.

WILLIAM G. BETZ.
